W. O. ASHE

LOCOMOTIVE FRAME

Filed Jan. 20, 1925

FIG. 1

FIG. 2

FIG. 3

INVENTOR
WILLIAM O. ASHE
or Cornwall, Bedell & James, Attn:

UNITED STATES PATENT OFFICE.

WILLIAM O. ASHE, OF ST. LOUIS, MISSOURI, ASSIGNOR TO COMMONWEALTH STEEL COMPANY, OF ST. LOUIS, MISSOURI, A CORPORATION OF NEW JERSEY.

LOCOMOTIVE FRAME.

Application filed January 20, 1925. Serial No. 3,585.

To all whom it may concern:

- Be it known that I, WILLIAM O. ASHE, a citizen of the United States, residing at St. Louis, Missouri, have invented a certain new and useful Improvement in Locomotive Frames, of which the following is a specification, such as will enable others skilled in the art to which it appertains to make and use the same.
- 10 My invention relates generally to locomotives and more particularly to the bed or frame which is carried by the driving wheels and serves as a support for the body of the locomotive.
- 15 The object of my invention is to provide a locomotive bed, the side frames of which, including the customary parts, are formed integrally with a boiler support upon the front end and with a foot or deck plate on the rear end.

The drawings illustrate the adaptation of my invention to a switching type of locomotive referred to in Whyte's System of Locomotive Classification as 060. It is to be understood though that my invention is applicable to any type or size locomotive bed used for switching or other purposes.

Another object of my invention is to provide a double drawbar pocket in the foot plate. This pocket is also to be an integral part of the frame.

In the drawings which indicate a preferred embodiment of my invention,—

Figure 1 is a side view of a locomotive bed or frame.

Figure 2 is a top plan view of one-half of the locomotive frame.

Figure 3 is a rear view showing the double drawbar pockets.

Figure 4 is a front view, partly in section, showing the front end boiler support.

The numeral 1 in the drawings indicates one of a pair of locomotive side frames formed integrally with and connected by various cross members 2. Side frames 1 are provided with driving box pedestals 3 and brake hanger lugs 4 which are also formed integrally with the main body of the locomotive bed. The cradle forming members 5 are integral with the various other parts and extend rearwardly of the rear pedestal boxes.

3. Foot plate 6 is integral with and joins together cradle forming members 5 at their rearward ends. Double drawbar pockets 7 and 8 are formed integral with foot plates 6,

making a one-piece construction of the rear end of the locomotive bed.

At the front end of the locomotive bed is a boiler supporting member 9 which is formed integrally with the side frames 1. Included in this boiler supporting member are an exhaust steam passageway 10 and a live steam passageway 11.

All of the above-mentioned parts are formed in one piece which prevents relative movement of the various parts and makes a substantially stronger locomotive bed than one which is assembled and uses the same amount of steel. It is a corollary that a locomotive bed cast in my improved method will be lighter in weight than one of corresponding strength made of a plurality of parts which are assembled by bolts, rivets and the like, because of the fact that it is made of one piece. The cost of manufacturing my improved locomotive bed is much cheaper than that of the ordinary form because there is no necessity of assembling the parts. By avoiding this I also avoid a large amount of machine work which would be a necessary operation on the crude castings to put them in condition for assembly.

I claim:

1. In combination with a locomotive frame, a boiler support formed integral therewith.
2. An integral locomotive frame including a front end boiler support and a foot plate.
3. A locomotive frame and a foot plate having a drawbar pocket therein formed integral with said frame.
4. A locomotive frame and a foot plate having a double drawbar pocket therein formed integral with said frame.
5. An integral locomotive frame including driving box pedestals, brake hanger lugs, a front end boiler support, and a foot plate having a drawbar pocket therein.
6. An integral locomotive frame including driving box pedestals, brake hanger lugs, a front end boiler support, and a foot plate having a double drawbar pocket therein.
7. A locomotive frame having formed integral therewith a front end boiler support, said boiler support being provided with an exhaust steam passageway.
8. A locomotive frame having formed integral therewith a front end boiler support, said boiler support being provided with a live steam passageway.

9. A locomotive frame having formed integral therewith a front end boiler support, said boiler support being provided with an exhaust steam passageway and a live steam passageway.
10. A locomotive frame comprising two spaced members and a front end boiler support formed with and joining said spaced members.
11. A locomotive frame comprising two spaced members, a front end boiler support, and a foot plate, said foot plate and boiler support being formed with and joining said spaced members.

In testimony whereof I hereunto affix my ¹⁶ signature this 6th day of January, 1925.

WILLIAM O. ASHE.
